UNITED STATES PATENT OFFICE.

WILLIAM B. KLINE AND GILES F. ROBINSON, OF BAY CITY, WISCONSIN.

DESIGN FOR A BAG-HOLDER.

SPECIFICATION forming part of Design No. 33,956, dated January 22, 1901.

Application filed December 20, 1900. Serial No. 40,590. Term of patent 7 years.

To all whom it may concern:

Be it known that we, WILLIAM B. KLINE and GILES F. ROBINSON, citizens of the United States, residing at Bay City, in the county of Pierce and State of Wisconsin, have invented and produced a certain new and original Design for Bag-Holders; and we do declare the following to be a full, clear, and exact description of the invention, such as will enable others skilled in the art to which it appertains to make and use the same.

The invention relates to a new and original design for a bag-holder; and it consists of the design shown in the accompanying drawings, in which—

Figure 1 is a perspective view, and Fig. 2 is a bottom plan view.

The leading feature of the design consists in the body portion 1, having arms 2 extend-

ing at right angles thereto, eyes 3 and 4, arranged in a horizontal plane, eyes 4', projecting downwardly and arranged in a vertical plane and terminating in a vertically-extending loop 5, coils 6, arranged near the innermost eyes 4', and coils 7, arranged near the outermost eyes and having prongs 8.

What we claim, and desire to secure by Letters Patent, is—

The design for a bag-holder as herein shown and described.

In testimony whereof we have hereunto set our hands in presence of two subscribing witnesses.

WILLIAM B. KLINE.
GILES F. ROBINSON.
